C. D. McLEAN

ELECTRIC CIRCULATION FLUID HEATER

Filed July 7, 1923

INVENTOR
Chas. D. McLean.

BY *A. M. M. Whistler*
ATTORNEY

UNITED STATES PATENT OFFICE.

CHARLES D. MCLEAN, OF BERLIN, NEW HAMPSHIRE, ASSIGNOR TO MECHANICAL & ELECTRICAL MANUFACTURING CO., INC., OF BERLIN, NEW HAMPSHIRE.

ELECTRIC CIRCULATION FLUID HEATER.

Application filed July 7, 1923. Serial No. 650,033.

To all whom it may concern:

Be it known that I, CHARLES D. MCLEAN, a citizen of the United States, residing at Berlin, in the county of Coos and State of 5 New Hampshire, have invented a new and Improved Electric Circulation Fluid Heater, of which the following is a specification.

The invention relates to certain new and useful improvements in fluid heaters of the 10 type stated and is more particularly directed to improvements in that type of fluid heater which is disclosed in Patent #1,460,025 issued under date of June 26, 1923 upon application Serial No. 561,941, filed May 18, 15 1922.

The invention primarily has for its object to provide a fluid heater of the type stated which is of a simple and economical construction, one that can be readily installed, 20 in an inexpensive manner, in the pipe line through which the fluid to be heated passes, and which is adapted to function so as to practically instantaneously heat the fluid as it passes therethrough.

More particularly the invention seeks to provide a water heater of the type stated which is of such construction that the same may be readily spliced into the house service water supply pipe in a reversible manner, that is, either end first, and so that the 25 water drawn from the said service pipe may be heated, while being drawn, when desired.

With the above objects in view my invention also includes those novel features of 30 construction, combination and arrangement of parts, all of which will be first fully described, then be specifically pointed out in the appended claims and illustrated in the accompanying drawing, in which:

Figure 1 is a part longitudinal section and elevation of my improved fluid heating appliance.

Figure 2 is an end view thereof showing the end cap as removed.

Figure 3 is a detail cross section taken through one of the hollow communicating heads.

In the drawing, in which like numerals of reference indicate like parts in all of the 50 figures, 1 represents an outer casing for the

fluid heating devices and the same is preferably constructed of fibrous or other like material such as will tend to render the same moisture proof, electrically non-conducting, strong and durable.

55

The outer casing 1 is provided with apertures 2, the purpose for which will later appear, and when the parts are operatively assembled is adapted to have the open ends thereof closed by end caps 3, preferably of 60 wood, which are held to their proper relation with the casing 1 by suitable screws 4. One of the end caps 3 is provided with an aperture 5 for accommodating a porcelain plug 6, the purpose of which will presently 65 appear.

Suitably mounted within the casing 1 I provide a plurality, two being shown, of heating units 7 which may be of any approved construction but which are preferably 70 constructed in the manner disclosed in my Patent #1,460,025, issued under date of June 26, 1923 upon application Serial No. 561,940, filed May 19, 1922.

Each such heating unit 7 is surrounded 75 by an inner casing 8, the opposite threaded ends of which thread into accommodating taps in hollow communicating heads 9 and the said heating units extend through the hollow portion of the heads 9, through suitable glands 10 provided therefor and secured in the said heads, and extend beyond the said glands where provision is made at 11 for properly connecting the heating units with an electric circuit so that, when the circuit is energized, the electric energy will cause the heating units to function in applying heat to the fluid passing through the appliance in a manner soon to be described.

In accomplishing the above stated purpose, 90 the wires 12 of the electric circuit pass through the porcelain block 6 of one of the caps 3 and connect as at 11 to one end of the pair of heating units illustrated in Figure 1. From this figure, it will be observed that 95 the other ends of the heating units there shown are connected by a cross plate 13 to properly complete the circuit so that electrical energy will pass through one of the wires 12 through the heating agencies in that 100

particular unit 7 through the cross plate 13 and back through the opposite heating unit 7 and the wire 12 connected thereto to properly complete the circuit.

- 5 Each of the hollow communicating heads 9 is provided with a lateral internally threaded extension into which is threaded a fluid pipe 14 adapted to extend through the apertures 2 in the casing 1 in a manner 10 for being readily connected with the source of supply of fluid to be heated, in a reversible manner.

By reference to Figures 1 and 3, it will be observed that the inner casings 8, which surround the heating unit 7, are of such size as to provide a fluid passage 15 between the same, and the said heating unit 7 is of such length and so mounted that the said fluid passages thus provided are in common 15 communication with the hollow of the heads 9 at the opposite ends thereof. Each heating unit 7 is provided with a spirally wound member 16 which extends through the fluid passage 15 and into the hollow of each head 20 9 in a manner for causing the fluid which passes through the passage 15, hereinbefore referred to, to take a spiral course, thereby retarding its passage through my improved heating appliance so that the same will be 25 more thoroughly brought into contact with the heating units, to be more thoroughly heated thereby.

For properly insulating the heating units contained within the outer casing 1 against 30 the cold outside air and also to provide for retaining the heat radiated from the said units, the casing 1 is filled with cork or other like substance 17. This compact filler of cork, or other similar material, also protects the units contained within the casing 1 against injury by contacting shocks and jars incident during the application of my 35 appliance within the house service pipe or other practical connection.

40 45 By reason of thus providing a communicating head at each end of a plurality of heating unit carrying inner casings, the hollow thereof is in common with all of the water passages formed between the said heating units and the inner casings, and by providing the pipe communications 14 between the said heads and the outside of the casing 1, it will be readily apparent 50 that a reversible structure is presented, that is, it is immaterial which of the pipes 14 be connected as the inlet or outlet pipe, as either will function universally.

55 By reason of providing the spiral pieces or members 16 in the spaces or fluid passages 15, the flow of circulation of the fluid is regulated in a manner whereby the desired quick heating of the same is effected.

60 It will be also readily understood that by providing the glands in the communicating heads for the heating units to pass

through, any possible expansion and contraction of the said units is taken care of and they are rendered pressure tight.

From the foregoing description, taken in connection with the accompanying drawing, it is thought the complete construction, operation and advantages of my invention will be readily understood by those skilled in the art to which it appertains.

What I claim is:

1. In a heating appliance of the class described, an outer casing, a plurality of heating units within said casing, means for connecting the heating units with an electric circuit, inner casings surrounding the heating units in a manner to provide a fluid passage therebetween, communicating heads for communicating with all of the fluid passages, and means whereby the communicating heads are in communication with the exterior of the outer casing and whereby attachment may be made with the source of supply of the fluid to be heated.

2. In a heating appliance of the class described, a plurality of heating units, means whereby said heating units may be connected with an electric circuit, casings for surrounding said heating units in a manner to provide fluid passages therebetween, a hollow communicating head in communication with all of the fluid passages at each end through which the heating units pass, and means whereby the said communicating heads may be reversibly connected with the source of supply of fluid to be heated.

3. In a heating appliance of the class described, a plurality of heating units, a casing surrounding each heating unit in a manner to provide a fluid passage therebetween, a hollow communicating head in communication with all of the fluid passages at each end, baffles in said fluid passages and extending into the hollow of said communicating heads, glands in each communicating head through which the heating units pass to extend beyond the heads, means whereby the extended ends of the heating units may be connected with an electric circuit, and means whereby the said communicating heads may be reversibly connected with the source of supply of fluid to be heated.

4. In a heating appliance of the class described, an outer casing, a plurality of heating units within said casing, an inner casing surrounding each heating unit in a manner to provide a fluid passage therebetween, a hollow communicating head to which the ends of the inner casings are connected at each end thereof and in a manner whereby the hollow of each such head will be common to all of the said fluid passages, baffles in said fluid passages and extending into the hollow of each communicating head, glands in each said head through which the heating units pass to extend beyond the said

heads, means at one end thereof whereby the extended ends of the heating units may be connected with the wires of an electric circuit, means at the other extended ends of the heating units for connecting the same electrically for completing the electric circuit, a fluid pipe connected with each com-

unicating head and projected through the outer casing for convenient reversible connection with the source of supply of fluid to be heated, and means in said outer casing whereby the heating units are insulated from cold air, moisture and shock.

CHARLES D. McLEAN.
